LESS THAN CARLOAD SHIPPER

Ralph V. Grayson, Atlanta, Ga.

Application April 9, 1934, Serial No. 719,776

10 Claims. (Cl. 62—91.5)

This invention relates to portable self-contained refrigerator units adapted to be employed in plurality in railroad or steamship transportation in the shipment of less than carload lots of products designed for different delivery points or which require to be maintained at different refrigerating temperatures enroute

The invention has for its principal object the provision of refrigerating shipping units as described, adapted to be removed from the car or hold of the vessel and set upon the dock or station platform without interrupting the refrigerating function of said units.

Another object of the invention is the provision of a portable less than carload shipping unit which when used in plurality so as to occupy the entire cargo space in the hold of the vessel or upon the car permits loading 100% of the lading space by virtue of the individual refrigerating system included in each unit. This cannot be done in the standard ice refrigerated car or hold on account of the necessity for providing ample space for circulation of air about the cargo parcels in order to obtain the necessary 20 refrigerating temperature in all parts of the lading space.

Still another object of the invention is the provision of a portable self-refrigerating less than carload shipping unit that requires no batteries or electrical instrumentalities, no steam or air connections, and which operates from power generated by the sublimation of a solid refrigerant.

A further object of the invention is the provision of a less than carload shipping unit including a thermal insulating refrigerated chamber associated with an evaporating tank individual to said unit and removable without the necessity of disturbing the refrigerated product, and means operable responsive to the pressure of gaseous refrigerant in said tank for creating a positive circulation throughout the refrigerated chamber.

Another object of the invention is the provision of an evaporator tank in association with the refrigerated chamber as above described in which conservation refrigerant is obtained by the provision of inner and outer annular spaces surrounding said tank, the outermost of which is maintained in vacuo while the inner annular space is controlled according to the refrigerating demands within the refrigerated chamber, the air in said inner annular space being normally inert and functioning as an insulating medium, but circulating through the inner annular space

and through the refrigerated chamber when the temperature of the latter has risen to a predetermined value.

Still another object of the invention is the provision of a motor for operating the means by which the air is circulated through said chamber only when the pressure of the gaseous refrigerant within the evaporator tank has attained predetermined pressure value.

Other objects of the invention will appear as the following description of a preferred and practical embodiment thereof proceeds.

In the drawings throughout the several figures of which the same characters of reference have been employed to designate identical parts: 15

Figure 1 is a plan view of the less than carload shipping unit partly shown in section;

Figure 2 is a cross section;

Figure 3 is a cross section taken at right angles to the section shown in Figure 2; 20

Figure 4 is a front elevation;

Figure 5 is a cross section through the removable evaporator tank taken along the line 5—5 of Figure 11;

Figure 6 is a longitudinal view of thermostatic means for controlling the dampers associated with the evaporator tank, part being shown in section;

Figure 7 is a longitudinal section through the fluid pressure motor which actuates the dampers; 30

Figure 8 is a section through the control valve which supplies fluid pressure to the motor;

Figure 9 is the fragmentary view showing the seating face of the valve;

Figure 10 is a positive view of the valve; and 35

Figure 11 is a longitudinal section through the evaporator tank.

Referring now in detail to the several figures the numeral 1 represents in general the less than carload shipper which comprises an outer casing 2 formed by corrugated side and end walls 3 and 4, respectively, and top and bottom walls 5 and 6, respectively. Within the casing 2 is an enclosure 7 of smaller dimensions arranged so as to leave a space 8 surrounding said enclosure on all sides. 40 This space is filled with any suitable fibrous or other porous insulating material 9. Since the walls of the enclosure 7 will be subjected to varying low ranges of temperature while the walls of the casing 2 will be exposed to atmospheric temperature changes, provision is made for preventing the eventual disintegration of the unity of the enclosure with respect to the casing by suspending the enclosure within the casing. This is accomplished by means of angle brackets 10 welded

or otherwise suitably secured across the corners of the outer casing, best shown in Figure 1, and by providing projecting plates 11 from the top corner portions of the enclosure 7, the plates 11 resting upon the angle brackets and being welded at their points of contact 12. The metallic leakage 8 between the enclosure 7 and the casing 2 is limited to the extremely small area represented by the point of weld 12. At all other points, excepting where provision is made for the reception of the evaporator tank, the enclosure 7 is spaced from the casing 2 by a layer of insulation. Since the enclosure is suspended from the casing at a plurality of points lying in the same plane it is obvious that relative elongation of the casing to the enclosure will not have any disruptive effect upon the points of weld nor will it impart strains to the well structure either of the enclosure or casing.

The shipper 1 is preferably supported by casters 13, one under each corner of the bottom, one pair of these being preferably rotatable in a fixed axial direction while the other pair swivel upon vertical axes. At their upper corners the shippers are preferably provided with rings 14. The shippers are designed to be arranged side by side upon a flat car or suitably positioned in the hold of a vessel. They are lifted when the delivery point is reached by a suitable mechanical hoist having hooks co-operating with the rings 14 and by means of which the shippers are placed upon a station platform or dock. The casters afford means for pushing them around in any desired direction upon the platform and also provide space beneath said shippers for the insertion of the forward end of a hand truck by means of which the individual shipping units can be transported from place to place.

The top walls 5 of the shipping units 1 slope from a central ridge 15, constituting a roof for shedding rain. In the middle of the roof and extending from back to front of the shipper is an arcuate valley 16 and in the middle is a hatchway 17 leading into the chamber within the enclosure 7. The concave valley acts as a slideway for receiving the evaporator tank 18 and the hatchway 17 affords an opening into the refrigerated chamber which is closed by the evaporator tank when the latter is in place. The evaporator tank has certain protuberances 19 and 20 which will presently be explained and these are accommodated through the opening in the hatchway. A frame-like felt pad 21 borders the hatchway 17, and upon this pad the evaporator tank rests forming a substantially fluid-tight seal with the wall of the refrigerated chamber. The evaporator tank 18 is held in place by flexible metal straps 22 secured at one end to the top wall of the casing as indicated at 23 in Figure 3 and connected by means of a turn buckle 24 to a lug 25 fixed to the top wall of the casing at the opposite side. The strap may be tightened against the evaporator tank by manipulating the turn buckle 24.

The evaporator tank comprises a container 26 preferably cylindrical permanently closed at one end and at the other having a removable header 27 through which the container may be charged with blocks of dry ice. The container 26 is surrounded by a shell 28 of larger diameter than said container constituting a jacket for the inner air space which immediately surrounds the container 26. Said jacket is in turn surrounded by a spaced shell 29. The inner air space communicates at upper and lower points with the refrigerated chamber by means of the inlet and outlet ports

19 and 20 constituting the protuberances hereinbefore referred to. The shells 28 and 29 are hermetically joined to the walls of said inlet and outlet ports so as to form a chamber from which the air may be suitably evacuated through a check valve 30.

The inlet and outlet ports are controlled by dampers 31 and 32 interconnected in a manner presently to be described and thermostatically controlled responsive to the temperature of the refrigerated chamber so as to remain closed, rendering the air within the shell 28 inert and adding to the thermal isolation of the container 26, when the refrigerating demands of the refrigerated chamber are small, but opening so as to provide a convectional flow of the air of said refrigerated chamber through the air space within the shell 28 when the demands of the refrigerated chamber exceed the determined value at which the thermostatic control operates. A baffle 48 is arranged in the air space within the shell 28 and between the inlet and outlet ports 19 and 20 so as to determine a unidirectional flow of air through said air space. The baffle is secured as by welding against one wall of said air space, but slightly spaced from the other as at 49 to defeat the continuity of a thermal leakage passage from the container 26 to the shell 28.

Thermal isolation of said container from said shell is further enhanced through the nature of supports which sustain the container 26 in spaced relation to the shell 28. These it will be observed from Figure 5 consist of lugs 50 preferably of triangular cross section welded or secured at their bases to one of said members, either the container 26 or shell 28 and bearing with their apical edges against the other of said members. Heat leakage is thus confined to the very small area of contact between said apical edges and the wall which they engage.

Between the shells 28 and 29 and in the evacuated chamber are small cylindrical spacers 51 welded to one of said shells and making line contact with the other.

Normally, when the dampers are closed very little sublimation of the solid refrigerant within the container 26 takes place and but little pressure is generated in the evaporator tank. On the other hand, when the dampers are open and the relatively warm air from the refrigerated chamber is circulating upward through the inlet 19 and outward through the outlet 20, the solid refrigerant is sublimed at a relatively rapid rate and considerable pressure is stored in the evaporator tank. This pressure is made use of when a predetermined pressure value has been exceeded in circulating air through the refrigerated chamber by means of a turbo-blower unit 33 comprising a turbine 34 and the blower 35 driven by said turbine. The blower is supplied with gaseous refrigerant under pressure by a conduit 36 communicating with the evaporator tank. The turbine exhausts through a conduit 37 which discharges into the insulating space between the top of the enclosure 7 and the casing 2. The conduit 37 is preferably formed with convolutions 38 so as to save to the refrigerated chamber the waste refrigerating capacity remaining in the exhaust gas from the turbine 34. Since the carbon dioxide gas is heavier than air, it percolates the fibrous insulating material in the space between the enclosure 7 and casing 2, descends to the bottom of said space and fills said space to the top, finally exhausting to atmosphere through a suitable aperture 39.

Since the rate of evaporation of the refrigerant in the evaporator tank is in general at too slow a rate to continuously generate sufficient pressure to operate the blower 34, an automatic pressure valve 40 is intercalated in the conduit 36, controlling said conduit so as to keep it closed until a predetermined pressure value has been built up within the evaporator tank and then opening it to transmit said pressure to the blower. Thus the operation of the blower is intermittent.

The blower has an inlet 41 taking air from the top of the refrigerated chamber and an outlet 42 which extends down to one of the bottom edges of the enclosure 7 at which point it debouches into a pipe 43 extending preferably substantially the full length of said edges. The bottom wall of the enclosure 7 has corrugations 44 defining between them airways, beneath the goods stored in said shipping units and which goods rest upon the peaks of said corrugations. The pipe 43 is provided with a plurality of laterals 45 extending through the spaces between said corrugations and beneath the goods and said laterals are perforated as at 46 and 47 permitting the air from said blower to be discharged beneath the shipment and at numerous points quite uniformly distributed on the underside of said shipment.

The thermostatic means for operating the dampers 31 and 32 comprise a bulb 52 adapted to be suitably arranged in the refrigerated chamber for containing a volatile fluid, said bulb communicating with a sylphon 53, the expansive or contractive movements of which oscillate a valve 54 controlling the admission of gaseous refrigerant under pressure to the piston chamber 55 of a fluid pressure motor 56. Said motor has a piston 57 actuated by the fluid pressure within the chamber 55 and reciprocating a link 58 connected to hinged levers 59 to which said dampers are secured.

The adjustment of the thermostatic control may be effected by a dial 60 forming a turn buckle at the ends of threaded sections of the rod which connected the sylphon to the valve whereby the time of opening said valve may be changed.

The valve is preferably of the oscillating type sliding upon its seat. It is shown in Figure 10 as having a frusto-conical seating surface 61 which slides as indicated in Figure 8 upon a frusto-conical seat having a port 62 communicating with the pressure chamber of the motor, and a vent port 63. The valve has a through-port 64 opening at one end in the seating surface and adapted to register with the port 62. The other end of the through-ports opens into a chamber 65 which communicates by means of a tube 66 with the conduit 36. This is the open position of the valve. The seating surface also has an arcuate channel 67 which in another position of the valve bridges the ports 62 and 63 discharging the pressure within the piston chamber 55 and permitting the return of the piston 57 under the urge of the spring 68. Upon this return movement of the piston the dampers 31 and 32 close.

The shipping unit is filled through a refrigerator door 69 of usual construction.

When the evaporator tank has become exhausted, it may be charged by removing the head and filling it with chunks of dry ice. It is not necessary each time it is charged to remove the evaporator tank from the unit. Occasionally, however, the evaporator tank will require replacement through need of repair and for other causes. It can be readily removed merely by loosening the turn-buckles 34, and unlatching the straps

22 upon making two pipe disconnections within the unit 1, namely uncoupling the pipe 36 which conducts gaseous refrigerant to the blower and disconnecting the tube 66 which supplies pressure to the thermal motor, the evaporator tank is free 5 for removal and replacement.

While I have in the above disclosure described what I believe to be a preferred and practical embodiment of my invention, it is to be understood that the details of construction as shown 10 and described are merely by way of example and not to be construed as limiting the scope of the invention as claimed.

What I claim is:

1. Self-refrigerating shipping unit comprising 15 an outer casing and an inner enclosure having an insulating space therebetween, said inner enclosure defining a refrigerated chamber, means for refrigerating said chamber, and means suspending said enclosure solely at spaced points adjacent 20 the top of said enclosure and casing to permit thermal elongation of said enclosure independently of said casing, said points of suspension having the minimum cross section commensurate with necessary supporting strength, so as to minimize 25 heat leakage from said enclosure to said casing.

2. Self-refrigerating shipping unit as claimed in claim 1, the suspending means comprising angle brackets subtending the corners of said casing and plates extending from the corners of 30 said enclosure resting upon said angle supports and secured thereto.

3. Self-refrigerating shipping unit comprising an outer corrugated casing and an inner enclosure, having an insulating space therebetween, 35 said inner enclosure being suspended from the outer casing adjacent the top, porous insulating material filling said insulating space, said enclosure defining a refrigerated chamber, means within said chamber for circulating air therethrough, a 40 fluid pressure motor for operating said air circulating means, a detachable evaporator associated with said refrigerated chamber adapted to contain a sublimating refrigerant and to retain the gas evolving from said refrigerant under pressure, a 45 conduit establishing communication between said evaporator and said motor for supplying gaseous refrigerant under pressure to said motor, and a valve in said conduit controlling the passage of gaseous refrigerant therethrough opening only 50 upon a predetermined pressure value of said refrigerant.

4. Self-refrigerating shipping unit as claimed in claim 3, the exhaust from said motor discharging into said insulating space. 55

5. Self-refrigerating shipping unit as claimed in claim 3, the bottom wall of said enclosure having elevations for supporting the refrigerated product thereupon and defining flues therebetween, said air circulating means including 60 branch pipes discharging within said flues.

6. Self-refrigerating shipping unit comprising an outer casing and an inner enclosure having an insulating space therebetween, the top of said shipping unit being formed with a hatch extending through the top walls of said casing and enclosure, an evaporating tank for sublimating refrigerant adapted to seat upon said hatch, a turbo-blower unit within the chamber defined by said enclosure, the blower element of said unit 65 being arranged to circulate air from the top of said chamber to the lower part thereof, the turbine element of said unit being adapted to have its inlet connected to said evaporator tank and its outlet to the space between said casing and 70 75

enclosure, said turbine being operated by gaseous refrigerant under pressure from said evaporating tank, means for inhibiting the passage of gaseous refrigerant from said evaporating tank to said turbine until a determined pressure value has been built up in said evaporating tank, means forming a jacket surrounding said evaporator tank having inlet and outlet ports at different levels, said ports extending through said hatch and communicating with the refrigerated chamber, dampers mounted on said evaporator tank for controlling said inlet and outlet ports, and thermo-motive means carried by said evaporator tank and responsive to the temperature of said refrigerated chamber for controlling said dampers arranged to open them when the refrigerating demands are relatively great and close them when said demands are relatively small.

7. Self-refrigerating shipping unit as claimed in claim 6, said evaporator tank including an outer shell enclosing a surrounding space in which an insulating vacuum is maintained.

8. Self-refrigerating shipping unit comprising an outer casing and an inner enclosure having an insulating space therebetween, the top of said shipping unit being formed with a concave channel providing a slide-way for a correspondingly shaped evaporator tank, a hatch extending through the bottom wall of said slide-way forming an opening into the refrigerated chamber within said enclosure, an evaporating tank for a sublimating refrigerant adapted to seat upon said hatch and substantially seal the same, a turbo-blower unit within said refrigerated chamber, the blower element of which being arranged to circulate air from the top of said chamber to the lower part thereof, the turbine element of said unit being adapted to have its inlet connected to said evaporator tank and its outlet space between said casing and enclosure, said turbine being operated by gaseous refrigerant

under pressure, derived from said evaporating tank, and means for inhibiting the supply of gaseous refrigerant from said turbine to said evaporator tank until a determined pressure value has been built up in said evaporator tank. 5

9. Self-refrigerating shipping unit as claimed in claim 8, said evaporator comprising a container and concentric spaced shells surrounding said container, the inner shell forming with said container an air space, the outer shell forming with the inner shell an evacuated space, inlet and outlet ports at different levels communicating with said air space, dampers carried by said tank controlling said inlet and outlet ports, and thermo-motive means also carried by said evaporator tank and responsive to temperature changes within the refrigerated chamber for operating said dampers when the refrigerating demands are large and closing them when the refrigerating demands are relatively small. 10 15

10. Self-refrigerating shipping unit as claimed in claim 8, said evaporator comprising a container and concentric spaced shells surrounding said container, the inner shell forming with said container an air space, the outer shell forming with the inner shell an evacuated space, inlet and outlet ports at different levels communicating with said air space, dampers carried by said tank controlling said inlet and outlet ports, and thermo-motive means also carried by said evaporator tank and responsive to temperature changes within the refrigerated chamber for operating said dampers when the refrigerating demands are large and closing them when the refrigerating demands are relatively small, including spacers of triangular cross section between said container and inner shell making edge engagement with the latter, and cylindrical spacers between said shells making line contact therewith. 20 25 30 35 40

RALPH V. GRAYSON. 40
